UNITED STATES PATENT OFFICE.

DAVID P. STEWART, OF BUFFALO, NEW YORK.

PUMP.

SPECIFICATION forming part of Letters Patent No. 314,078, dated March 17, 1885.

Application filed April 9, 1884. (No model.)

To all whom it may concern:

Be it known that I, DAVID P. STEWART, of the city of Buffalo, in the county of Erie and State of New York, have invented new and useful Improvements in Feed-Pumps, of which the following is a specification.

This invention relates more particularly to that class of feed-pumps in which a reciprocating tubular plunger or piston is operated by means of an actuating-rod pivotally secured thereto, and which has an oscillating movement within the bore of the plunger.

The object of my invention is to provide a simple and durable means for securing the connecting-rod to the plunger or piston, whereby a firm connection between these parts is maintained at all times; and it consists of the improvements, which will be hereinafter described, and pointed out in the claims.

In the accompanying drawings, Figure 1 represents a vertical sectional elevation of a feed-pump provided with my improvements. Fig. 2 is a similar view at right angles to Fig. 1. Fig. 3 is a horizontal cross-section of the plunger, connecting-rod, and adjustable bearings. Fig. 4 is a top plan view of the plunger. Fig. 5 is an elevation of the end of the connecting-rod which is secured to the plunger. Fig. 6 is an elevation of one of the adjustable bearings.

Like letters of reference refer to like parts in the several figures.

A represents the pump-cylinder, which is cast with or otherwise secured to a frame, A', and provided with the usual inlet and outlet ports, a a'.

B represents the tubular plunger, and C the stuffing-box, through which the plunger B plays in the cylinder A, a reciprocating motion being imparted to the plunger B by means of the connecting-rod D and crank E. The upper end of the connecting-rod D is secured to the crank E, which is formed on the end of a horizontal shaft, e, journaled in bearings secured to the frame A'. Motion is imparted to the shaft e by a driving-pulley, G.

The opposite or lower end of the connecting-rod is provided with a T-shaped head or knuckle, d, having a cylindrical body, which is seated in a semicircular groove or recess, b, formed in the head b' of the plunger. The

groove b extends across the head b', and is preferably made large enough to receive the lower half of the cylindrical body of the knuckle d, the upper cylindrical surface of the knuckle 55 lying above the plane of the head b' of the plunger.

h h are two U-shaped bearings or caps, which rest upon the knuckle d on either side of the connecting-rod and within the tubular plunger, 60 and retain the knuckle d of the connecting-rod in its seat. The bearings or caps h are provided with vertical arms h', which extend upwardly to within a short distance from the top of the plunger. The outer vertical sides 65 of the arms h' and the bearings h are preferably curved to fit closely against the inner wall of the tubular plunger.

i i are two inwardly-projecting lugs or ears formed on diametrical opposite sides of the 70 cylindrical body of the plunger, as shown in Fig. 4. The lugs i are provided with screw-threaded openings, in which are inserted screw-bolts k, having jam-nuts k'. The ends of the bolts k below the lugs are preferably seated in 75 sockets formed in the upper end of the arms h', and retain the bearings or caps h in their proper position upon the knuckle d. The connecting-rod is in this manner firmly attached to the plunger, while the cylindrical 80 part of the knuckle and its bearings permit the requisite oscillatory movement of the connecting-rod within the bore of the plunger in adjusting itself to the movement of the crank.

Any wear resulting from the continuous 85 rocking movement of the knuckle or head d in its seat in reciprocating the piston can be readily taken up without removing any of the parts by means of the screw-bolts k, and the latter are firmly held in place from accidental 90 turning by the jam-nuts k'.

It is evident that my invention can be applied to engines and other machines in which a tubular plunger or piston and a connecting-rod pivoted thereto are employed.

I claim as my invention—

1. The combination, with the piston or plunger B, of the connecting-rod D, provided with a head or knuckle, d, bearings h, having vertical arms h', and screw-bolts k, substantially as set forth.

2. The combination, with the piston or

plunger B, having a groove or recess, b' , of a connecting-rod, D, provided with a knuckle, d , seated in said groove, bearings h , arms h' , and screw-bolts k , substantially as set forth.

5 3. The combination, with a tubular plunger, B, having a groove or recess, b' , and lugs i , of the connecting-rod D, provided with a T-shaped head or knuckle, d , bearings h , pro-

vided with vertical arms h' , screw-bolts k , and jam-nuts k' , substantially as set forth.

Witness my hand this 1st day of April, 1884.

DAVID P. STEWART.
